REMOTE ALARM CIRCUIT FOR WARNING LIGHTS OR THE LIKE

John H. Ganzenhuber, La Canada, Calif.

Application September 10, 1958, Serial No. 760,272

10 Claims. (Cl. 315—136)

This invention is directed to remote alarm circuits for warning or marker lights and, more particularly, to a circuit which provides a remote indication of the condition of warning lights on a tower or the like and which, where desired, automatically connects a replacement lamp in the lighting circuit when its companion lamp fails.

Antenna towers for television stations, microwave relay stations, radar stations and the like constitute hazards to aircraft in flight. Many governmental agencies have spent large periods of time and great sums of money in attempts to reduce the hazardous nature of such towers. One step which has been taken is the establishment of rigid standards of lighting for such towers and the requirement that any such lighting have a high degree of reliability. Because the towers are generally located at some distance from a manned control point and further, because some of the towers are so tall as to extend above some low hanging clouds it is imperative that the condition of the warning lights be reliably indicated to persons manning the facility which is utilizing the tower or towers. In the past various approaches have been taken to providing remote indication of warning lamp condition, for example, relays with series and shunt coils have been connected into the lamp lighting circuit connected to indicating lamps or the like so that when the current for the series coil is discontinued for an extended period a remote indication of that condition is given. However, such relays are expensive and have a limited amount of reliability over long periods of time. One of the problems that is involved is that in many tower lighting installations the lamps are flashed so that the current flowing to the lamp is intermittent and it is necessary to provide in the alarm or indicating circuits a time delay which prevents actuation of the alarm device when the normal flashing operation is occurring but will cause actuation of the alarm device if the lamp burns out.

Therefore, it is an object of this invention to provide for a warning light circuit an improved remote indication circuit showing the condition of the warning light.

It is a further object of this invention to provide for a tower lighting system a remote indication circuit which will respond to a lamp burn-out condition but will not respond to intermittent flashing of the lamp in the tower lighting circuit.

It is a still further object of this invention to provide for a tower lighting circuit a remote indication and lamp transfer circuit which will automatically indicate the burning out of one of the lamps in the tower lighting circuit and at the same time will transfer power to a second or auxiliary lamp circuit so as to provide continued and reliable marking of the tower.

According to the present invention a current transformer has its primary connected in series with the warning lamp circuit and has its secondary connected to the resistive element of a thermal time delay relay which is adjusted to have its response time longer than the time between successive flashes of the warning lamp, where

2

a flashing warning lamp is used, and has its control contacts connected for controlling a remote alarm or indicating device directly or through an auxiliary relay. A lamp transfer relay may be provided with its control winding either shunting the alarm or indicating device or provided with power through the contacts of a relay controlled by the time-delay relay which actuates the alarm or indicating device.

The features of the present invention which are believed to be novel are set forth with particularity in the appended claims. The present invention, both as to its organization and manner of operation, together with further objects and advantages thereof, may best be understood by reference to the following description, taken in connection with the accompanying drawings, in which,

Figure 1 is a circuit diagram, partially in block form, showing a remote alarm and lamp transfer circuit according to the present invention.

Figure 2 is a circuit diagram of the alarm circuit portion of the circuit of Figure 1.

In Figure 1, alternating current power for the warning lamp circuit is applied to terminals 10 and 11 and flows through contact arm 13 of relay 14, contact terminal 15 with which contact arm 13 is normally in electrical contact, through primary 12, lamp 16 which is located on the tower or obstruction, and circuit interrupter 17, in the event that warning lamp 16 is of the flashing type. Of course, lamp 16 instead of being a sole lamp may be replaced by a plurality of lamps in parallel. Secondary 18 of current transformer 19 is coupled to the input terminal 41 and 42 of heating element 20 in thermal time-delay relay 21. Load resistor 40 shunts secondary winding 18 of current transformer 19. Controlled contacts 22 and 23 of thermal relay 21 are connected to control terminals 24 and 25 of the remote indicator or alarm 26. Output control terminals 27 and 28 of alarm 26 are coupled to control winding 29 of transfer relay 14. Power to operate alarm 26 and relay 14 is applied at power input terminals 30 and 31. Alternatively, of course, relay 14 may be controlled directly by contacts 22 and 23 on relay 21.

The circuit of Figure 1 operates as follows. The alternating current applied to terminals 10 and 11 is applied in an interrupted form through the primary 12 of current transformer 19 and the closed contacts 13 and 15 of relay 14 to lamp 16. Circuit interrupter 17 is an electromechanically driven switch of any one of several conventional varieties. The intermittent current flowing through primary 12 induces a current through the heating element 20 of thermal time-delay relay 21. The heating of element 20 in relay 21 opens the circuit between contacts 22 and 23. Alarm 26 thus remains unactivated as long as a predetermined current flows at least intermittently through primary 12. The response time of relay 21 is longer than the time between successive periods of current flow produced by circuit interrupter 17 so that for normal operation of flashing lamp 16 the contacts 22 and 23 will remain disconnected in the alarm and the alarm 26 will not be actuated. Of course, it is possible to provide in alarm 26 a relay which requires contacts 22 and 23 to be closed during normal operation of the lamp 16 in order that alarm 26 be not actuated and which actuates alarm 26 when contacts 22 and 23 are open circuited. Such a circuit would provide an additional fail-safe feature in that if relay 21 ceased to function, alarm 26 would be actuated. Further, the closing of contacts 22 and 23 could be used to actuate an indicator of normal lamp operation. Also, if relay 21 is of the single-pole double-throw type the normally closed contact can be used to activate an alarm, whereas the normally open contact can be used to operate a "lights on" indicator.

In any event, when alarm 26 is actuated, power is provided to control coil 29 of transfer relay 14 pulling contact arm 13 away from contact 15 and into contact with electrical contact 32 thus disconnecting power from lamp 16 and connecting it to lamp 33. Thus, the lamp transfer function is performed simultaneously with the alarm function. Of course, it is possible to provide either of these functions without the other. Further, the lamps 16 or 33 need not be flashed for this invention to apply. In addition the remote indicating lamp may simply shunt lamp 33.

The alarm circuit of Figure 2 is designed to work with a thermal relay 21 which exhibits an open circuit between controlled terminals 22 and 23 when element 20 is heated. Thus, when lamp 16 of Figure 1 is operating properly, terminals 24 and 25 of Figure 2 will be open circuited, alarm or indicator lamp 34 will remain unlit, and no power will be provided to control winding 29 of transfer relay 14. However, in the event that lamp 16 burns out, current will cease flowing through primary winding 12 of current transformer 19 in Figure 1 and heating element 20 will cool until contacts 22 and 23 are no longer open circuited but are closed circuited. This will complete the circuit from power input terminals 30 and 31 to control winding 35 of relay 36. Contact arm 37 will be pulled into electrical connection with terminal 27 and contact arm 38 will be pulled into electrical connection with terminal 39. The electrical connection between contact arm 37 and terminal 27 will apply power to control winding 29 of transfer relay 14 thus pulling contact arm 13 away from terminal 15 and into electrical connection with terminal 32, thus completing the electrical circuit to lamp 33. At the same time, contact arm 38 when in electrical connection with terminal 39 will complete the electrical circuit through warning lamp 34. Of course, warning lamp 34 may be replaced by a buzzer, bell or the like, any one of which may be located locally or remotely.

With the circuit of Figure 2, malfunctioning of current transformer 19, relay 21 or lamp 16 will produce an alarm or remote indication so that repair may be made at once.

It is to be noted that if heating element 20 of thermal relay 21 should burn out, very high potential surges will tend to appear across secondary 18 of current transformer 19 as circuit interrupter 17 operates. These high potentials, if permitted to appear, would break down the secondary insulation and destroy the transformer. To prevent this occurrence load resistor 40 is provided in shunt with secondary 18.

Thus, there has been provided by this invention a reliable and accurate alarm and automatic transfer circuit for warning lights on towers or obstructions.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

I claim:

1. A circuit for indicating the condition of an electrical load including: a transformer, said transformer having a primary winding and a secondary winding, said primary winding being connected electrically in series with said load; a thermal relay having first and second control terminals and a pair of controlled contacts shiftable between two respective electrical conditions in response to a change in the voltage to said first and second control terminals; said secondary winding being connected between said first and second control terminals; an alarm circuit having a pair of input control terminals, an indicating device and a pair of power terminals, said input control terminals being connected to said con-

trolled contacts, and means coupled between said input control terminals and said indicating device for coupling said power terminals to said indicating device only when said controlled contacts are in a predetermined one of said two electrical conditions.

2. Apparatus according to claim 1 in which said predetermined one of said two electrical conditions of said controlled contacts is a closed circuit condition and the other is an open circuit condition.

3. Apparatus according to claim 1 in which said predetermined one of said two electrical conditions of said controlled contacts is an open circuit condition and the other is a closed circuit condition.

4. Apparatus according to claim 1 in which said means for coupling said power terminals to said indicating device comprises a relay.

5. Apparatus according to claim 2 in which said indicating device is a lamp.

6. Apparatus according to claim 3 in which said indicating device is a lamp.

7. Apparatus according to claim 1 in which said remote electrical load is at least one lamp.

8. Apparatus according to claim 4 in which said remote electrical load is at least one lamp and said indicating device is a lamp.

9. Apparatus according to claim 1 in which said indicating device has first and second terminals and said means for coupling said indicating device to said power terminals includes an electromagnetic relay having first

30 and second control coil terminals and a pair of normally open contacts, one of said pair of power terminals being connected to said first control coil terminal and to said first terminal of said indicating device, the other of said pair of power terminals being coupled through said input control terminals of said alarm circuit and through said controlled contacts of said thermal relay to said second control coil terminal and through said pair of normally open contacts of said electromagnetic relay to said second terminal of said indicating device.

10. A circuit for detecting the failure of a first lamp and automatically shifting to a second lamp including: first and second lamps each having first and second terminals; a transformer, said transformer having a primary winding and a secondary winding; a thermal relay having first and second control terminals and a pair of controlled contacts, said controlled contacts being shiftable from an electrically closed condition to an electrically open condition in response to the application of an electrical voltage to said first and second control terminals;

45 an alarm circuit having a pair of input control terminals, an indicating device, said indicating device having first and second terminals, and a pair of power terminals, said input control terminals being coupled to each other through said controlled contacts; a first electromagnetic relay having first and second control coil terminals and first and second pairs of normally open contacts; a second electromagnetic relay having third and fourth control coil terminals, first and second output contacts and an input arm normally in contact with said first output contact but movable into contact with said second output contact upon application of a voltage between said third and fourth control coil terminals; one of said pair of power terminals being connected to said first and third control coil terminals and to said first terminal of said indicating device; the other of said power terminals being coupled through said input control terminals of said alarm circuit and through said controlled contacts to said second control coil terminal,

50 through said first pair of normally open contacts of said first electromagnetic relay to said second terminal of said indicating device and through said second pair of normally open contacts of said first electromagnetic relay to said fourth control coil terminal of said second

55 electromagnetic relay.

60
